SEPARABLE BINDER RING ASSEMBLY

Isidore Spinner, Chicago, Ill., assignor to Plastic Binding Corporation, Chicago, Ill., a corporation of Delaware

Application July 2, 1947, Serial No. 758,507

2 Claims. (Cl. 206—56)

1

This invention relates to binder rings and to a method of making the same, particularly to binder rings of resilient plastic material for use in binding a stack of pages, or for holding curtains, draperies or the like on a rod, or for other purposes.

In my Patent No. 2,435,561, issued February 3, 1948, there is shown and described an improved method of making binder rings whereby a large number of such rings may be made in a single operation. Briefly, that method consists in scoring or cutting a sheet of plastic to provide a plurality of parallel abutting fingers that are held together along a very small fractional part of their abutting lines of contact, the sheet being then curled into tubular form. This forms a plurality of rings held together and wherein the rings are readily separable one from another for individual use. I have found that when such rings are separated there remains a rough spot at the point of separation. This interferes with the insertion of the ring through holes or slots in the material or materials being held thereby and may even injure the material. It is one of the objects of the present invention to provide a curled tube of individual rings which are held together only at one or more spaced points of very narrow width so that the rings may be readily separated from one another, and wherein the point of holding of the rings is along an edge thereof that does not have any appreciable sliding contact with the articles that are to be bound by the ring.

In accordance with the present invention a sheet of plastic material that is to be formed into a plurality of rings is cut to form the individual fingers that are to constitute the rings, with abutting fingers physically separate from one another along their entire length. The fingers are held together by a backbone which constitutes the edge of the sheet. Each finger remains joined to the backbone at a narrow length on the crosswise edge of the finger.

The attainment of the above and further objects of the present invention will be apparent from the following specification taken in conjunction with the accompanying drawing forming a part thereof.

In the drawing:

Figure 1 is a plan view of a blank from which a plurality of rings is to be made simultaneously;

Figure 2 is an end view of the blank of Figure 1;

Figure 3 is an enlarged sectional view taken along the line 3—3 of Figure 1;

2

Figure 4 is a perspective view of the blank of Figure 1 curled into tubular form and illustrating one end ring severed from the rest of the tube;

Figure 5 is an end view of one of the rings of Figure 4;

Figure 6 is a perspective view of a stack of pages bound by the ring of the present invention; and

Figure 7 is a diagrammatical view illustrating the manner of curling the blank of Figure 1 into the tubular form of Figure 4.

In the accompanying drawing like reference numerals designate like parts throughout.

Reference may now be had more particularly to Figures 1, 2 and 3. There is provided a blank 1 of Celluloid, cellulose acetate, "Pyroxylin," "Vinylite," or other plastic resilient material which when heated can be formed to the desired shape and retains its thus formed shape upon cooling. The blank of Figure 1 is of a generally rectangular shape and has a series of uniformly spaced parallel lines of cut 3—3 extending through the entire thickness of the strip and in a direction transversely of the strip almost but not quite the complete length of the strip. Adjacent lines of cut 3 are joined at opposite ends by discontinuous smooth curved lines of cut 4. The lines of cut 4 extend through the entire thickness of the material and they merge with the lines of cut 3 along smooth curves. Each curved line of cut 4 is discontinuous at one location, indicated at 5, which is in a position corresponding to the crest of the curve. The lines of cut thus form a series of fingers 6 and backbones 7 and 8, each finger being joined to both backbones 7 and 8 at the locations 5. The backbones thus lightly hold the fingers together in sheet form.

The blank of Figure 1 is curled into a cylinder or tube shape 9. This is done by placing the blank on a flexible sheet that rests upon a heated table then, by holding the flexible sheet taut, the flexible sheet together with the blank 1 are then rolled around a mandrel to curl the blank into tubular form, the blank being held by the sheet around the mandrel for a length of time sufficient to permit the plastic material to cool to a temperature such that it retains its tubular shape.

Figure 4 shows the blank 1 curled to form a tube 9. The blank is curled through an arc exceeding 360° by an amount more than the maximum widths of the two backbones so that the opposite edges of each finger 6 overlap one another, as may be seen from Figure 4. The maximum temperature to which the material is heated preceding or during the curling operation is in-

sufficient to cause the material to become bonded together either at the lines of cut or at the overlapped surfaces of the curled sheet. The lines of cut 3 extend circumferentially around the tube thus formed.

The tube 9 constitutes an article of manufacture and sale. The purchaser or user of this tube may break off the rings, one at a time, as individual rings are needed. The break in each case is at the junctures 5 between the ring and the inner and outer backbones. All of the circumferential edges of the thus formed ring are smooth, being of the degree of smoothness determined by the dies used in forming the cuts 3. There are no rough parts at the side edges on the ring. The only place where there may be any degree of roughness on each ring is the place or places where the ring has been broken from the backbones, namely, at the places 5.

The ring 9 may be used for binding a stack of sheets of paper together. This may be accomplished by merely manually opening the end 10 of the ring and then threading the ring through a line of perforations in a stack of pages. When the end 10 is released it springs back to the position of Figure 5 due to its own resiliency, and is in pressure contact with the subjacent part 11 overlapped thereby, thus holding the ring closed. This occurs even if the ring had previously been opened more than 180°. A plurality of rings, indicated at 12-12, may be threaded through separate groups of aligned perforations in a stack of pages, binding the stack of pages together, as illustrated in Figure 6.

Figure 7 illustrates one method of making the binder cylinder 9 of Figure 4. The blank 1 rests on a flexible cloth sheet 15 on a heated table 16. The sheet 15 is rolled around a mandrel 17 and passes around a rod 18, the two ends of the sheet 15 being held taut. The mandrel 17 and the rod 18 roll from right to left on the table 16 to curl the binder. A machine for thus forming a binder is illustrated in the patent to Christian B. Nelson and myself, No. 2,211,743, issued August 30, 1940, to which reference may be had.

I have herein illustrated a sheet wherein the individual fingers 6 are held together by two backbones 7 and 8. It is within the purview of the present invention to omit one of those two backbones so that the fingers are held together at only one end.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. An article of manufacture comprising a con-

tinuous flat sheet weakened by a plurality of parallel uniformly spaced lines of cut each extending as one continuous line from adjacent one edge of the sheet to adjacent the opposite edge and extending through the full thickness of the sheet to form a plurality of fingers with adjacent fingers in abutment throughout their entire length, and with each line of cut terminating short of the longitudinal edges of the sheet to leave a longitudinally extending strip at each end of the sheet, said strips constituting two backbones extending at right angles to the fingers and with each finger extending lengthwise from one backbone to the other, each finger being joined to both backbones, said sheet having curved lines of cut almost but not quite severing the fingers from the backbones, whereby the fingers are held together by the backbones but are readily severed therefrom.

2. A plurality of side by side joined separable rings each adapted to be opened, said joined rings comprising a continuous sheet curled into tubular form with the edges of the sheet overlapping, the extent of overlap being less than 360°, the sheet being of resilient material and held in tubular shape by its own resiliency, the overlapped portions being physically separable to open the tube and the material being sufficiently resilient so that upon release of the opened overlapped portions of the tube those portions spring back under their own resiliency to complete the tube, the tube being cut along a plurality of uniformly spaced parallel lines each of which extends through the entire thickness of the material and around the entire periphery of the tube, and in a plane substantially at right angles to the longitudinal axis of the tube to facilitate separating the tube into a plurality of rings, there being curved lines of cut adjacent those opposite edges of the sheet between which the adjacent lines of cut extend, the curved lines of cut merging with the parallel lines of cut along smooth curves, leaving a narrow backbone between the curved lines of cut and the adjacent edges of the sheet, said backbones being joined to the rings adjacent the curved cuts to hold the rings together.
